TRAFFIC SIGNAL SYSTEM FOR NON-STOP NETWORKS

John K. Masten, Elmhurst, N.Y.

Application February 23, 1954, Serial No. 411,912

18 Claims. (Cl. 340—40)

My invention relates particularly to the system, and process, of operating and controlling pedestrian and vehicular traffic, and especially urban traffic, although it is applicable to crossing road systems generally to control the traffic thereon.

An object of my invention is to obtain maximum non-stop traffic-conductance and so as to obtain compatibility of many types of roads. In this way, one of the objects of my invention is to attain a continuous coordinated flow of traffic on the different crossing roads such as primary roads which are of high conductance and secondary roads which are of lesser conductance, in which traffic is allowed to travel long distances in a cycle of time for example through eight interval spaces on any one road in one given time cycle, while permitting non-stop traffic on crossing roads. The light signals, for instance red and green, are so arranged as to turn, on various points of the 8-point cycle. In other words, by my invention, there is attained a constant progression of the traffic, at speeds that are proportionate to the block distances, for example at equal speeds where the block distances are equal, without interference. Furthermore, my system affords rapid conductance of a large volume of vehicular traffic while allowing proper time for crossing by pedestrians at the cross-intersections. My invention, also, includes the provision of similar groups of signals so arranged as to permit the uninterrupted synchronized travel of traffic trains along the roads and across their intersections.

Heretofore, with respect to traffic progression, it has been considered that the ideal city block would be of impractically large size, for example $\frac{1}{4}$ mile between intersections, in order to permit fair progressive speeds and volume, and a sufficiently long cycle to insure the safety of pedestrians at all crossings. It is an object of the present invention to provide a method for obtaining good speed, volume and safety in a network of roads where the blocks are small to permit thereby high conductance network progression of traffic in areas where it has not previously been attained, thus providing a way to relieve the congestion within many of our present cities and to provide planning for future urban areas. Thus, the conception of the needed city block should be changed as small blocks can contribute to great conductance rather than congestion.

It is an object of this invention to attain greater overall utility and compatibility than either a network of completely two-way or completely one-way conventional arrangements can provide, by controlling traffic in a special manner in a network of roads which are predetermined for primary and secondary use, to provide a degree of traffic conductance in urban areas that greatly surpasses that which is possible with former controls, especially where small blocks preclude satisfactory use of other processes, while at the same time making it possible to retain or restore at will some two-way roads. This enables a greater degree of compatibility to be attained.

A further object is to effect a primary and secondary road traffic control in a network, to provide a wide

2

primary separation and also a wide secondary separation, in such a way as not to produce conflict and so that each supplements the other, to secure, in zones containing small blocks, certain inherent advantages of large blocks, as for example, increased progressive speeds, while also securing the many advantages of small blocks such as the greater total square footage of roadway provided, ease of access, convenience for pedestrian and automotive traffic, suitability for mass transit accommodations, and 10 commercial utility.

This method is especially recommended, for example, in areas such as the central business sections of Los Angeles, California, and Pittsburgh, Pennsylvania.

Each signal may be operated by a cam rotated by the 15 alternating current cycle, that may be considered to be divided into eight equal intervals or eight equidistant points of time on the circumference of the cam, so that each particular signal cam is started at a particular one of the eight time-points. Thus, vertical and horizontal 20 volumes of traffic in a network of roads are apportioned according to the span of the cam in its particular point of rotation at each particular crossing in the road system.

While my invention is capable of embodiment in many 25 different forms, for the purpose of illustration I have described only certain forms and modifications of my invention and have shown only certain illustrations thereof in the accompanying drawings, in which a one-way road is shown by a single line, a two-way road is shown by a double line, a primary road of relatively high conductance 30 is shown by a heavier line than in the case of a secondary road generally of relatively lower conductance or a tertiary or optionally restricted road, and the tertiary roads are shown in dotted lines.

Where two-line roads are indicated, however, it should 35 be understood that by permitting traffic to progress both ways traffic may obviously be confined to either way at option, if desired, and that such employment may not only be necessary on some streets but frequently desirable especially in dual employment, of which Fig. 7 is an 40 example.

Fig. 1 is a diagrammatic representation of a unit system of roads using signal lights, each being actuated in a 45 complete cycle of operation divided into eight time-points, in which the primary block system is comprised of urban blocks shown as being approximately square, with two sets of crossing one-way primary roads and alternating directions of travel, having between one of the sets of parallel one-way roads an interposed set of parallel two-way secondary roads, this being a substantially ideal city street arrangement;

Fig. 2 is a like view of a system such as in Fig. 1, but 50 having added thereto a set of parallel tertiary two-way roads located at right angles to the secondary set of two-way roads, and in which the tertiary roads may not be operated for through traffic, but in which all of the primary and secondary roads are provided for continuous 55 through traffic;

Fig. 3 is a view similar to Fig. 1, in which the secondary 60 two-way roads extend differently through some of the urban blocks, to illustrate the adaptability to different road arrangements;

Fig. 4 is a similar view to that shown in Fig. 2, but in which some of the secondary roads are at right angles to other secondary roads operated to produce continuous traffic thereon;

Fig. 5 is an urban block system, having interposed between each set of parallel primary roads, a set of parallel one-way secondary roads;

Fig. 6 is another block system, but in which one set of parallel primary roads has interposed another set of parallel primary one-way roads as well as two sets of parallel two-way secondary roads;

Fig. 7 is a similar view of a system like that in Fig. 6, but in which there is added an interposed system of tertiary or additional two-way roads, located at right angles to the other two-way roads;

Fig. 8 is a similar view to Fig. 6, but in which the primary blocks are not square and not uniformly the same, but longer in one direction than the other;

Fig. 9 symbolizes the electrical or mechanical actuation of the respective signals through the illustration of cams, any one signal being actuated in the manner well known in the art, to illustrate the relative positions of signal cams at the identical moment the signals bearing the time-point "2" are actuated to horizontal Go. If at this instant the cams of all signals "2" have just changed their phase to horizontal Go, it is apparent that the cams of all signals bearing the time-point "3" are positioned 45° behind, so as to be actuated to horizontal Go upon the following $\frac{1}{8}$ cycle of time. The cams of other signals are similarly offset in time and degree, one from the other. This offset relation is retained as the cams revolve; and

Fig. 10 is an illustration showing the platoon arrangement of Figs. 2 and 4 at the moment shown therein when the signals at time-point positions "2" are changing to horizontal Go.

Fig. 9, thus, shows, as examples of the eight positions, diagrammatically, the 1, 2, 3 and 4 positions of the cams at the moment the "2" position is being actuated, as at the upper left-hand corner of Fig. 5, and in every other "2" position in all the figures, each of the rotary cams 10, 11, 12 and 13, and their corresponding light positions 14, 15, 16 and 17 being shifted by the cam surfaces co-acting with electrical or mechanical light-shifting contacts or elements 22, 23, 24 and 25. The cams 10, 11, 12 and 13 are adjustably held by screws 26, 27, 28 and 29 on constant speed shafts 30, 31, 32 and 33, all driven, for example as in electric clocks, at the same speed from any source of electrical current, for instance an urban electrical A.-C. current, having a given cycle of alternation. However, any other means of coordinating and synchronizing the signals through previously known means can be used instead. The spans of the cams could be increased, or decreased, to any extent desired, as shown at 34. One of these red and green signal lights is located at each of the road crossings, each having, for example, a 180° segment for each of two signal positions, making a 360° cycle of rotation of the cam in a given time cycle, for instance a 60-second cycle, all of which cams and signal lights may be constructed alike so that the said cycle may be divided into the eight time-points. Each cam located at its respective crossing may be set manually or otherwise at its particular 45° offset time-point, in order that at a given instant of time all the cams at the various road crossings will have been set at their respective one of said eight time-points, as indicated by the numbers on the respective road crossings shown in Figs. 1 to 8, indicating the time-point at which each signal begins its cycle in relation to all other signals in a common direction.

In the drawings, the examples of road systems therein embody signal devices for roads running substantially at right angles to one another and which, for convenience, may be referred to as being vertical or horizontal, respectively. Each signal device is understood to contain at least Go and Stop signals for the crossings, and while additional caution signals may be included, they will not be considered herein. Initially, in the explanation of my invention, the description will deal with signal devices which exhibit Go and Stop signals to the crossing directions for equal time periods, each corresponding to the duration of one-half the same chosen signal cycle for all the signals. Thus, in one position of the signal, it will display Go to the horizontal direction and Stop to the vertical direction and vice versa, and each signal device will be switched from one position to the other at half

cycle time periods. The signal devices are identified according to the cycle points at which they are set in the time cycle when they switch to a different position in a common direction of traffic. The cycling of the signal

devices takes into account the time needed for pedestrians to cross an intersection, for which 30 seconds may be generally considered a minimum amount of time, which means that the Stop signal may be on for about 30 seconds and off for an equal time, making the signal cycle 60 seconds.

In each of the systems herein, it is assumed, for convenience, that the traffic is permitted to travel at a similar rate on all roads of the network where the road crossings are uniformly distant, or at other speeds proportionate to any variations in interval spaces.

In the Figs. 1 to 8, the networks include primary one-way roads. These one-way roads and the combinations thereof with other one-way and two-way roads are found to be far superior to simultaneous two-way systems, and also superior to a mere one-way primary network.

The networks in the said Figs. 1 to 8 can be conveniently considered as being within Fig. 5, or modifications or alterations thereof, as shown in the respective Figs. 1 to 8. Thus, I shall refer principally to Fig. 5, initially.

The network therein comprises roads 1-H to 8-H from top to bottom, and then repeating so that the 9th horizontal road employs a signal system directly parallel to the first road, and 8 vertical roads 1-V to 8-V left to right, then repeating so that the 9th vertical road employs a signal system directly parallel to the first vertical road, so that the signal systems upon said roads have the following properties and arrangements which automatically enable the continuous coordinated flow of traffic to be attained.

Road 1-H.—Starting at a given position 1-H, 1-V, in Figs. 1 to 8, which is associated with a signal commencing its horizontal Go period at a 2nd point of time in the cycle, there extends a primary 1st horizontal series road to the right so that successive horizontal Go signals at positions 1-V through 8-V upon road 1-H start at time-points 2, 3, 4, 5, 6, 7, 8 and 1, respectively, then repeating the series, so that signals commence their cycles horizontally on successive time-point lags of $\frac{1}{8}$ cycle per interval-space, so that one-way platoons of traffic are permitted to travel to the right through successive Go periods of signals at a conforming interval-space rate and so that crossing vertical platoons are permitted to follow only on the vertical Go periods of opposite cycle phase to the horizontal Go phase.

Road 1-V.—As a counterpart to said primary 1st horizontal series road 1-H, from position 1-H, 1-V, there extends a primary 1st vertical series road 1-V downwardly so that successive horizontal Go signals, at positions 1-H through 8-H upon road 1-V start at time-points 2, 3, 4, 5, 6, 7, 8 and 1, respectively, then repeating the series, so that each signal commences its cycle horizontally in downward vertical relation one to the other, on subsequent time-point lags of $\frac{1}{8}$ cycle per interval-space. Thus, crossing horizontal platoons are permitted subsequent passage on said horizontal Go periods, so that one-way platoons of traffic are permitted to travel downwardly in the direction of time-point lag, through successive vertical Go periods of opposite cycle phase to the horizontal Go signals at conforming interval-space rates.

Road 2-H.—From the position 2-H, 1-V, there extends a permissible secondary 2nd horizontal series road to the right, so that successive horizontal Go signals at positions 1-V through 8-V upon road 2-H, start at the time-points 3, 4, 3, 4, 7, 8, 7, 8, respectively, then repeating the series, so that secondary one-way platoons of traffic traveling to the right at interval-space rates are permitted passage through all signals approached, so that said secondary one-way platoons become shorter and thus have a lesser conductance than primary road platoons and remain parallel to those on road 1-H and so that

one-way platoons are restricted to interval-space rates at the positions where road 2-H crosses 1-V, 2-V, 5-V and 6-V without any special offset to the horizontal Go period (but so that a further 2-interval substitution of Stop for Go at the beginning of the horizontal Go period is also permissible but not essential at crossings 3-V, 4-V, 7-V and 8-V which otherwise turn horizontal Go before being approached where constant speed is maintained); and so that road 2-H may be two-way yet its signals may still operate on long display periods, in the event that (see Figs. 3 and 4) vertical traffic is not permitted to cross at 4-V and 8-V (or in the event that long signal displays are not necessary at the said crossings, as for example on narrow roads, then the signals at said crossings, if existent, may be changed concurrently with the arrival of the frequent progressive platoons), so that the additional return platoons to the left, parallel the longer platoons of the same direction upon road 3-H, with the leftward traffic automatically being restrained to conforming rates at crossings 7-V, 6-V, 3-V and 2-V, respectively, upon road 2-H, and so that crossing vertical platoons follow only on the vertical Go periods (of opposite cycle phase to the horizontal Go signals).

Road 2-V.—As a counterpart to the said secondary 2nd horizontal series road, but from the relative position 1-H, 2-V, there extends a permissible secondary 2nd vertical series road 2-V toward the base, so that successive horizontal Go signals, at positions 1-H through 8-H upon road 2-V, proceed downwardly at the associated time-points 3, 4, 3, 4, 7, 8, 7, 8, respectively, then repeating the series; so that crossing horizontal platoons are permitted passage at the aforesaid positions on horizontal Go periods of the associated time-points; and so that secondary one-way platoons of traffic traveling downwardly at interval-space rates are permitted passage through all signals approached upon the following vertical Go periods of opposite cycle phase to horizontal Go signals; so that the shorter said secondary one-way platoons, providing less conductance remain parallel to those on primary road 1-V, and so that said one-way platoons are restricted to interval-space rates at the positions where the road 2-V crosses 1-H, 2-H, 5-H and 6-H without any special offset to the vertical Go period (but so that a further two-interval substitution of Stop for Go at the beginning of the vertical Go period is also permissible but not essential at other crossings at 3-H, 4-H, 7-H and 8-H, which otherwise turn vertical Go before being approached, where constant speed is maintained); and, further, so that road 2-V may be two-way yet its signals may still operate on long display periods, see Figs. 1, 2, 3, 4, 6, 7 and 8, in the event that horizontal secondary traffic is not permitted to cross at 4-H and 8-H (or in the event that long signal displays are not necessary at the said crossings, as for example on narrow roads, then the signals at said crossings, if existent, may be changed concurrently with the arrival of the frequent progressive platoons), so that the additional return platoons, traveling toward the top, parallel the longer platoons of the same direction upon road 3-V, with upward traffic being automatically restrained to conforming rates at crossings 7-H, 6-H, 3-H, 2-H, respectively, upon road 2-V.

Road 3-H.—From the relative position 3-H, 1-V there extends a primary 3rd horizontal series road to the right, so that horizontal Go signals at positions 1-V through 8-V upon road 3-H, start at precessional time-points 4, 3, 2, 1, 8, 7, 6, 5, respectively, then repeating the series, so that the signals commence their cycles horizontally to the right on subsequent time-point leads of $\frac{1}{8}$ cycle per interval-space, so that one-way platoons of traffic are permitted to travel to the left in the direction of lag (opposite to lead) through successive Go periods of signals at a conforming interval-space rate, and so that crossing vertical platoons are permitted to follow only

on the vertical Go periods of opposite cycle phase to horizontal Go periods at each signal.

Road 3-V.—As a counterpart to said 3rd horizontal series road, but from the relative position 1-H, 3-V, there extends a primary 3rd vertical road toward the base, so that horizontal Go signals at positions 1-H through 8-H upon road 3-V, with the signals precessing downwardly, also start at the associated time-points 4, 3, 2, 1, 8, 7, 6, 5, respectively, then repeating the series (so that crossing horizontal platoons are permitted associated passage at the aforesaid positions on said horizontal Go periods); so that each signal commences its cycle horizontally in downward vertical relation, one to the other, on time-point leads of $\frac{1}{8}$ cycle per interval-space, and so that one-way platoons of traffic are permitted to travel upwardly in the direction of time-point lag, through succeeding vertical Go periods (of opposite cycle phase to horizontal Go) at a conforming interval-space rate.

Road 4-H.—From the relative position 4-H, 1-V there extends a permissible secondary 4th horizontal series road to the right, so that horizontal Go signals at positions 1-V through 8-V upon road 4-H, start at the time-points 5, 4, 1, 2, 1, 8, 5, 6, respectively, then repeating the series, so that secondary one-way platoons of traffic traveling toward the left at interval-space rates are permitted passage through all signals approached, so that the shorter said secondary one-way platoons remain parallel to those on road 3-H, so that said one-way platoons are restricted to interval-space rates at the positions toward the left where road 4-H crosses 8-V, 6-V, 5-V, 4-V, 2-V and 1-V, without any special offset to the horizontal Go period (but so that a further two-interval substitution of Stop for Go at the beginning of the horizontal Go period is also permissible but not essential at crossings 7-V and 3-V which otherwise turn horizontal Go before being approached, where constant speed is maintained; and, further, so that road 4-H may be two-way yet its signals may still operate on long display periods, in the event that vertical traffic is not permitted to cross at 2-V and 6-V (or in the event that long signal displays are not necessary at the said crossings, as for example on narrow roads, then the signals at said crossings, if existent, may be changed concurrently with the arrival of the frequent progressive platoons), see Figs. 3 and 4, so that the additional secondary 4-H return platoons to the left, parallel the longer primary platoons of the same direction upon road 3-H, with the left traffic automatically being restrained to conforming rates at crossings 7-V, 6-V, 3-V and 2-V, respectively, upon road 2-H; and so that crossing vertical platoons follow only on the vertical Go periods (of opposite cycle phase to horizontal Go periods) at each signal.

Road 4-V.—As a counterpart to the said secondary 4th horizontal road, but from the relative position 1-H, 4-V there extends toward the base, a permissible secondary 4th vertical series road, so that horizontal Go signals at positions 1-H through 8-H upon road 4-V, start at the time-points 5, 4, 1, 2, 1, 8, 5, 6, respectively, then repeating the series (so that crossing horizontal platoons are permitted passage at the aforesaid positions on horizontal Go periods of the associated time-points); so that secondary one-way platoons of traffic traveling upwardly at interval-space rates are permitted passage through all signals approached upon the vertical Go periods of opposite cycle phase to horizontal Go periods so that the shorter said secondary one-way platoons remain parallel to those on road 3-V, so that said one-way platoons are restricted upwardly to interval-space rates at the positions where road 4-V crosses 8-H, 6-H, 5-H, 4-H, 2-H and 1-H without any special offset to the vertical Go period (but so that a further two-interval substitution of Stop for Go at the beginning of the vertical Go period is also permissible but not essential at crossings 7-H and 3-H), see Fig. 5;

and, further, so that road 4-V may be two-way yet its signals may still operate on long display periods, in the event that horizontal secondary traffic is not permitted to cross at 2-H and 6-H (or in the event that long signal displays are not necessary at the said crossings, as for example on narrow roads, then the signals at said crossings, if existent, may be changed concurrently with the arrival of the frequent progressive platoons), see Figs. 1, 2, 3, 4, 6, 7 and 8, so that the additional return platoons progress downwardly, parallel to the longer platoons of the same direction upon 5-V, with downward traffic being automatically restrained to conforming rates at crossings 3-H, 4-H, 7-H and 8-H, respectively, upon road 4-V.

Road 5-H.—From the relative position 5-H, 1-V, there extends a primary 5th horizontal series road to the right, so that horizontal Go signals at positions 1-V through 8-V on road 5-H start at succeeding time-points 6, 7, 8, 1, 2, 3, 4 and 5, respectively, then repeating the series, so that the signals commence their cycles horizontally to the right on subsequent time-point lags of $\frac{1}{8}$ cycle per interval-space, so that one-way platoons of traffic are permitted to travel to the right through successive Go periods of signals at a conforming time interval space rate; so that said horizontal platoons upon roads 5-H travel in positions alternate to those on 1-H; and so that crossing vertical platoons are permitted to follow only on the vertical Go periods of opposite cycle phase to the horizontal Go periods at each signal.

Road 5-V.—As a counterpart to said primary 5th horizontal series road, but from the relative position of 1-H, 5-V, there extends a primary 5th vertical series road toward the base, so that horizontal Go signals at positions 1-H through 8-H on road 5-V start at succeeding time-points 6, 7, 8, 1, 2, 3, 4, 5, respectively, then repeating the series (so that crossing horizontal platoons are permitted passage at the aforesaid positions on horizontal Go periods of the associated time-points); so that each signal commences its cycle horizontally in downward (vertical) relation to the others on subsequent time-point lags of $\frac{1}{8}$ cycle per interval-space, and so that one-way platoons of traffic are permitted to travel downwardly at a conforming interval-space rate, through succeeding vertical Go periods (of opposite cycle phase to horizontal Go periods); and so that the said vertical platoons upon road 5-V travel in positions alternate to those on 1-V.

Road 6-H.—From the relative position 6-H, 1-V there extends a permissible secondary 2nd horizontal series road to the right, so that horizontal Go signals at positions 1-V through 8-V upon road 6-H start at the time-points, 7, 8, 7, 8, 3, 4, 3, 4, respectively, then repeating the series, so that secondary one-way platoons of traffic traveling to the right at interval-space rates are permitted passage through all signals approached; so that the shorter said secondary one-way platoons remain parallel to those on road 5-H, so that said one-way platoons are restricted within interval-space rates at the positions where road 6-H crosses 1-V, 2-V, 5-V and 6-V without any special offset to the horizontal Go period (but so that a further two-interval substitution of Stop for Go at the beginning of the horizontal Go period is also permissible but not essential at other crossings 3-V, 4-V, 7-V and 8-V which otherwise turn horizontal Go before being approached, where constant speed is maintained), so that the said horizontal platoons upon road 6-H travel in positions alternate to those on roads 2-H; and, further, so that road 6-H may be two-way yet its signals may still operate on long display periods, in the event that vertical secondary traffic is not permitted to cross at 4-V and 8-V (or in the event that long signal displays are not necessary at the said crossings, as for example on narrow roads, then the signals at said crossings, if existent, may be changed concurrently with the arrival of the frequent progressive platoons), see Figs. 3 and 4, so that the additional return platoons to the left, parallel the longer platoons of the same direction upon road 7-H, with leftward traffic being automatically re-

strained to conforming rates at crossings 7-V, 6-V, 3-V and 2-V, respectively, upon road 6-H; and so that crossing vertical platoons are permitted to follow only on the vertical Go periods of opposite cycle phase to horizontal

5 Go periods at each signal.

Road 6-V.—As a counterpart to the said secondary 6th horizontal road, but from the relative position 1-H, 6-V, there extends toward the base, a permissible secondary 6th vertical series road, so that horizontal Go signals at positions 1-H through 8-H upon road 6-V, proceed downwardly, at the associated time-points 7, 8, 7, 8, 3, 4, 3, 4, respectively, then repeating the series (so that crossing horizontal platoons are permitted passage at the aforesaid positions on horizontal Go periods of the associated time-points); so that secondary one-way platoons of traffic traveling downwardly at interval-space rates are permitted passage through all signals approached upon the following vertical Go periods of opposite phase to horizontal Go periods; so that the shorter said secondary one-way platoons remain parallel to those on road 5-V, so that said one-way platoons are restricted to interval-space rates at the positions where road 6-V crosses 1-H, 2-H, 5-H and 6-H without any special offset to the vertical Go period (but so that a further two-interval substitution of 20 Stop for Go at the beginning of the vertical Go period is also permissible but not essential at crossings 3-H, 4-H, 7-H and 8-H which otherwise turn vertical Go before being approached, where constant speed is maintained; so that the said vertical platoons upon roads 6-V travel in 25 positions alternate to those on 2-V; and, further, so that road 6-V may be two-way yet its signals may still operate on long display periods in the event that horizontal secondary traffic is not permitted to cross at 4-H and 8-H (or in the event that long signal displays are not necessary 30 at the said crossings, as for example on narrow roads, then the signals at said crossings, if existent, may be changed concurrently with the arrival of the frequent progressive platoons), see Figs. 1, 2, 3, 4, 6, 7 and 8, so that the additional return platoons traveling upwardly, 35 parallel the longer platoons of the same direction upon road 7-V, with upward traffic on 6-V restrained to conforming rates at crossings 7-H, 6-H, 3-H and 2-H, respectively.

Road 7-H.—From a relative positon 7-H, 1-V there extends a primary 7th horizontal series road to the right, 45 so that horizontal Go signals at positions 1-V through 8-V upon road 7-H, start at precessional time-points 8, 7, 6, 5, 4, 3, 2, 1, respectively, then repeating the series, so that the signals commence their cycles horizontally to the right on time-point leads of $\frac{1}{8}$ cycle per interval-space, so that one-way platoons of traffic are permitted to travel to the left in the direction of lag, through successive Go periods of signals at a conforming time interval-space rate; so that the horizontal platoons upon roads 7-H travel in a position alternate to 50 those on roads 3-H; and so that crossing vertical platoons are permitted to follow only on the vertical Go periods of opposite cycle phase to horizontal Go periods at each signal.

Road 7-V.—As a counterpart to said primary 7th horizontal series road, but from the relative position 1-H, 7-V, there extends a primary 7th vertical road toward the base, so that horizontal Go signals, with the signals precessing downwardly, at positions 1-H through 8-H, start at the associated time-points 8, 7, 6, 5, 4, 3, 2, 1, respectively, then repeating the series (so that crossing horizontal platoons are permitted associated passage at the aforesaid positions on said horizontal Go periods); so that each signal commences its cycle horizontally in 60 downward vertical relation one to the other, on time-point leads of $\frac{1}{8}$ cycle per interval-space, and so that one-way platoons of traffic are permitted to travel upwardly in the direction of time-point lag through succeeding vertical Go periods of opposite phase to horizontal Go periods, at a conforming time interval-space rate;

so that the said vertical platoons upon roads 7-V travel in a position alternate to those on 3-V.

Road 8-H.—From the relative position 8-H, 1-V, there extends a permissible secondary 8th horizontal series road to the right, so that horizontal Go signals at positions 1-V through 8-V upon road 8-H start at the time-points 1, 8, 5, 6, 5, 4, 1, 2, respectively, then repeating the series, so that secondary one-way platoons of traffic traveling toward the left at interval-space rates are permitted passage through all signals approached; so that the shorter said secondary one-way platoons remain parallel to those on road 7-H, so that said one-way platoons are restricted to interval-space rates at the positions toward the left where road 8-H crosses 8-V, 6-V, 5-V, 4-V, 2-V and 1-V, without any special offset to the horizontal Go period (but so that a further two-interval substitution of Stop for Go at the beginning of the horizontal Go period is also permissible but not essential at crossings 7-V and 3-V which otherwise turn horizontal Go before being approached, where constant speed is maintained); so that the said horizontal platoons upon road 8-H travel in positions alternate to those on road 4-H; and, further, so that the road 8-H may be two-way yet its signals may still operate on long display periods, in the event that vertical secondary traffic is not permitted to cross at 2-V and 6-V (or in the event that long signal displays are not necessary at the said crossings, as for example on narrow roads, then the signals at said crossings, if existent, may be changed concurrently with the arrival of the frequent progressive platoons), see Figs. 3 and 4, so that the additional return platoons to the right, parallel the longer platoons of the same direction upon road 1-H with right traffic automatically being restrained to conforming rates at crossings 3-V, 4-V, 7-V and 8-V, respectively, upon road 8-H; and so that crossing vertical platoons follow only on the vertical Go periods of opposite cycle phase to the horizontal Go periods at each signal.

Road 8-V.—As a counterpart to the said secondary 8th horizontal road but from the relative position 1-H, 8-V, there extends toward the base a permissible secondary 8th vertical series road, so that horizontal Go signals, at positions 1-H through 8-H upon road 8-V, start at the time-points 1, 8, 5, 6, 4, 1, 2, respectively, then repeating the series (so that crossing horizontal platoons are permitted passage at the aforesaid positions on horizontal Go periods of the associated time-points), and so that secondary one-way platoons of traffic traveling upwardly at interval-space rates are permitted passage through all signals approached upon the vertical Go periods of a cycle phase opposite to the horizontal Go phase, so that the shorter said secondary one-way platoons remain parallel to those on road 7-V, so that said one-way platoons are restricted upwardly to interval-space rates at the positions where road 8-V crosses 8-H, 6-H, 5-H, 4-H, 2-H and 1-H, without any special offset to the vertical Go period (but so that a further two-interval substitution of Stop for Go at the beginning of the vertical Go period is also permissible but not essential at crossings 7-H and 3-H upon 8-V, which otherwise turn vertical Go before being approached, where constant speed is maintained); so that the said vertical platoons upon road 8-V travel in a position alternate to those on 4-V; and further, so that road 8-V may be two-way yet its signals may still operate on long display periods, in the event that horizontal traffic is not permitted to cross at 2-H and 6-H (or in the event that long signal displays are not necessary at the said crossings, as for example on narrow roads, then the signals at said crossings, if existent, may be changed concurrently with the arrival of the frequent progressive platoons), see Figs. 1, 2, 3, 4, 6, 7 and 8, so that the additional return platoons, traveling downwardly, parallel the longer platoons of the same direction upon road 1-V, with traffic automatically being restrained to con-

forming rates at crossings 3-H, 4-H, 7-H and 8-H, respectively, upon road 8-V. Further, there may be a permissible reduction of one time point in the time-point settings of the signals within local areas, located at 2-V and 6-V upon 2-H, 4-V and 8-V upon 4-H, 2-V and 6-V upon 6-H, 4-V and 8-V upon 8-H, see Figs. 2, 3, 4 and 7.

In the foregoing description, where two-way roads are introduced into the system, it is apparent that the number of secondary two-way through roads may be limited, for example, in Figs. 2 and 4, the dotted lines indicate roads reduced to tertiary status, there being road blocks introduced at certain time-point positions as designated by parenthesis marks. Said road blocks thereby permit the entrance and exit between one side of some of the two-way secondary roads and two-way tertiary roads, but the tertiary traffic may not cross secondary two-way traffic at such positions. It is evident that in such tertiary road arrangements, coordination is retained so that local tertiary traffic starting at the change of a signal may proceed at a conforming non-stop speed from one road block to the next.

As initially described with respect to Fig. 5, in Figs. 1 to 8 the platoons of through traffic may acquire interrelated positions. The platoon successions in these figures are disposed throughout the network with respect to the primary and secondary road basis and the time-division basis. However, it should be noted that if deviations therefrom occur, the juxtaposition of the primary and secondary through platoons, as well as their successions, may be, as stated, identified with the primary and secondary road basis, and by the platoon interrelations. Briefly, the flow of progressing through-platoons upon the secondary roads may be juxtaposed substantially to the side of the longer primary platoons upon the nearest primary road of the similar vehicle direction considered upon the said secondary road, whether the secondary road is one or two-way. In saturated traffic, the front of the platoons of traffic on the primary roads, 40 may repeatedly pass near the ends of the crossing primary platoons, that is to say the traffic of one phase may cross behind that of an opposite phase. Figs. 1, 2, 4, 5, 6 and 7 disclose a span which vehicles could traverse in a given cycle of time. It may be considered, however, that within each cycle-distance of a substantially 45 square area, arrangements, comprising eight one-way primaries and four two-way secondaries with permissible tertiary additions, are especially excellent for model localities. The systems may, of course, be larger or smaller.

The Fig. 10 illustrates by the indications of long heavy primary arrows, and by shorter light secondary arrows, the principal progressive platoons of traffic in one drawing. However, certain of these platoons may be restricted in each one of the systems as shown in Figs. 55 1 to 8, in order to permit equally long signal displays and, accordingly, permit the use of wide roads throughout a network without endangering the pedestrian. The squares in Fig. 10 may represent street blocks and the spaces may represent roads; however, both may be considered variable as to proportions and dimensions. The platoons are shown in the positions they would occupy 60 at that instant of time when the signals are at the point of operation as in Fig. 9, with the horizontal signal display at time-point positions "2" just turning Go. If each of the platoons is considered to move constantly forward in the direction of the arrow, all of the platoons shown, as well as those which would follow, may continually progress in true coordination without conflict 65 between them. For example, if all of the platoons were considered to be advanced in steps, the design relationship could be repeated each eight steps, so that the first and ninth steps would be similar, the second and tenth would be like each other, and so that the remaining steps 70 would also repeat in this manner. The platoon rela-

tion of each Fig. 1 to 5 may be illustrated by simply removing from Fig. 10 either the roads or crossings or platoon directions not provided in those figures. Special consideration is directed to those crossings which occur between diverse time-point positions at the road block indications, as indicated in Fig. 10 by the letters *a* and *b*. It may be seen that these are inherently short signal display positions by reason of the fact that short secondary platoons of traffic upon crossing two-way roads arrive at such positions from one of four directions at a time, as for example from the north, east, south or west and then repeating, as at crossing 2-V, 4-H in Fig. 2. In the Fig. 10, such arrivals may be ascertained as at the *a* positions, for example at 2-V, 4-H, where one platoon may be considered as having come from the west and the other as just arriving from the north. The order of succession at the *b* positions is from the counterwise relation of north, west, south and east, then repeating. Thus, each of the two types of positions may reflect either a clockwise or counter-clockwise property. It is apparent that different signal action may be permitted at said positions in the different figures. For example, in Figs. 2, 4, 5 and 7 such signals may permissibly operate signal displays equal in length to the signals at other crossing positions, rather than being limited to the inherent short display relation, and thereby wider roads are allowable than would otherwise be compatible with more rapidly shifting signals. In the Figs. 1 to 5, the platoons progress as illustrated in relation to Fig. 10, except that in each case the platoons are affected, as for example by the absence of different secondary roads as in Figs. 1 and 3, or by the absence of certain secondary platoons to effect one-way secondary operation as in Fig. 5, or by the center of the road blocking or absence of certain crossings at the parenthetical positions in Figs. 2 and 4, thereby to permit long signal displays at wide crossings. In Figs. 6, 7, and 8, wherein the roads are shown in pairs, the various platoons would be similarly disposed in pairs, Fig. 6 being comparable to Fig. 1, Fig. 7 to Fig. 2, and Fig. 8 modified from Fig. 6, 40 a difference in these three figures from Figs. 1 to 5 being that the platoons do not in all cases cross quite as closely to the ends of the other crossing platoons. The crossings *a* and *b* in Fig. 10 may also be similarly identified by the road designations in the other figures. Such positions in Fig. 5 are provided with time-point numbers such as would permit the signals to remain receptive to the platoons of one direction, without resorting to signal displays of shorter length. The signals in Figs. 1 to 8 may operate on long displays, yet this does not preclude the operation of certain signals to turn Go with arriving traffic. If the platoons of Fig. 10 are considered to be moving at the same speed, there would be no conflict. Accordingly, if the signals are operated from Stop to Go as the progressively coordinated platoons arrive at the intersections, a repetitive coordinated sequence would thereby result. Likewise, by establishing the signal sequence initially, it is apparent that the signals would then expedite the platoons as above described.

It is apparent that secondary road signals having a two-way progressive basis (as for example road 2-V at 5-H and 7-H) may be operated within a primary road system by reason of the fact the the signals repeat at certain crossings at either of opposite phases of a time cycle, although additional interposed signals are permitted. A secondary road thereby may possess certain inherent limitations of balanced two-way progressive conductance, even if employed in one-way use.

As an example of the utility of the system, referring to Fig. 1, if the system were applied to an area, wherein the blocks were 330 ft. by 660 ft. from road center to road center and pedestrians were allowed 30 seconds at each crossing, the signals thereby working on a 60 second cycle, the speed of continuous vehicle progression in the system would be 30 miles an hour. At approxi-

mate rates of walking by pedestrians, upon primary roads, utilizing either one or two minutes plus or minus $\frac{1}{6}$ minute for each short block and two or three or four minutes per long block plus or minus $\frac{1}{4}$ minute according to the direction, the pedestrians would always proceed past the blocks and street crossings without stopping the walking pace being slower if in the direction of vehicular traffic. In the design of street arrangement, it is also desirable that the longer directions of the oblong blocks correspond to the longer dimension of a city. The overall utility of Fig. 7 for vehicular traffic is even greater than in Fig. 1, assuming that two adjacent parallel primary roads with traffic in the same direction are acceptable.

The object of the articulated system in attaining exceptional performance may be accomplished by means of the examples disclosed. That it can be accomplished, may be supported through a principle of analysis which need not be considered in applying the process, but which may, nevertheless, assist in illustrating, in a uniform use thereof, the system's potential attributes and general character.

The conductance of any system may be considered the total of the conductances upon all roads within each square mile. The conductance of each road can be derived from the formula: Speed times the saturation factor. The speed is found to be, in miles per hour, equal to the distance in feet traveled in one cycle of time, divided by the cycle expressed in seconds, times

$$\frac{3600 \text{ seconds per hour}}{5280 \text{ feet per mile}}$$

It will be noted that the number of time-point positions of the signals in a Go position, at a given moment upon the primary roads, are in proportion:

$$\frac{\text{Duration of the Go period of a cycle}}{\text{Duration of complete cycle}}$$

so that the signals progress as a wave. For example, if each horizontal primary signal in the Figs. 1 to 5 were in a Go position $\frac{2}{3}$ of the time rather than $\frac{1}{2}$, then it follows that the signals are also in a Go position extending through $\frac{2}{3}$ of the horizontal road unit and the green wave moves as a group, within which there may be a platoon of moving cars. The secondary road relation to the primary roads is such that the alternating wave of pairs of same-number time-points may be interposed with non-conflicting and conforming signals so that the extent of the Go span of progressing signals never falls below the proportion of the expressed saturation factors as follows:

The saturation factor for each through road in Figs. 1 to 8 may be found as follows:

For the primary horizontal roads in Figs. 1 to 5

55 Saturation factor =

$$\frac{\text{duration of horizontal Go period of a cycle}}{\text{duration of complete cycle}}$$

for the primary vertical roads in Figs. 1 to 8

60 Saturation factor =

$$\frac{\text{duration of vertical Go period of cycle}}{\text{duration of complete cycle}}$$

For the primary horizontal roads in Figs. 6, 7 and 8

65 Saturation factor =

$$\frac{\text{duration of horizontal Go period of a cycle}}{\text{duration of complete cycle}} \quad 16$$

because certain signals which operate in pairs are a distance apart equal to the space traveled in $\frac{1}{16}$ of the cycle.

For the secondary roads in all figures

$$\text{Saturation factor} = \frac{\text{duration of Go period of a cycle}}{\text{duration of complete cycle}} \quad 4$$

13

because certain signals which operate simultaneously with each other are a distance apart equal to the space traveled in $\frac{1}{4}$ of the cycle of time, where the said secondary roads cross primary roads.

As an example of this analysis, it may be considered that the Fig. 6, employing 60 second cycles, has been adapted to a locality having 40 short blocks to the mile in one direction and 10 long blocks to the mile in the other direction. Its conductance would then be calculated as in the following table:

Number of roads	$\times$	Speed	$\times$	Saturation factor	$=$	Combined road conductance
10 hor. pri.	$\times$	$\frac{2112}{60} \times \frac{3600}{5280}$	$\times$	$(\frac{30}{60} - \frac{1}{16})$	$=$	105
20 ver. pri.	$\times$	$\frac{2112}{60} \times \frac{3600}{5280}$	$\times$	$\frac{30}{60}$	$=$	240
20 ver. sec.	$\times$	$\frac{2112}{60} \times \frac{3600}{5280}$	$\times$	$(\frac{30}{60} - \frac{1}{4})$	$=$	120
Conductance total						465

It should be noted that if the blocks of the above example were larger, the resulting exceptional speed in Fig. 6 would require a longer cycle than 60 seconds to slow down the traffic, thereby granting the pedestrian a much greater time allowance than 30 seconds to cross each street with the longer cycle.

It is apparent, also, that these systems can be employed in cases where excessively wide roads would prevent the use of other systems dependent upon short cycles for conducting traffic at reasonable speeds.

The principle of evaluation of effectiveness is such that, in the analysis of any road system with a given cycle, for example 60 seconds, the expansion or contraction of the distances within the unit system to fit within a given area produces the same conductance, because upon the expansion of the distances there is a faster speed and there are fewer roads, and because upon contraction of the distances there is a slower speed and there are more roads within the same given area, and because in both cases the number of roads multiplied by the speed is equal. Thus, in the analysis of any kind of system, its utility can be clearly and consistently evaluated, as above, regardless of road concentration and by further analysis in this way between any different systems the individual merit thereof can be evaluated comparatively by this principle to determine their utility and effectiveness. The following are the comparative ratings regardless of road concentration within a given square mile, where 60 second time cycles are employed, with equal horizontal and vertical division of the cycle, with respect to progressive through traffic upon primary and secondary roads in the respective Figs. 1 to 8:

Figs. 1 to 4	300
Fig. 5	360
Figs. 6 and 7	465
Fig. 8	390

As the above consideration relates to speed times saturation, the platoon lengths of both sides of two-way streets may, for convenience, be considered as one. For example, if two-way secondary platoons are two blocks long in both the N and S directions, this is equivalent to a platoon only two blocks long combining both sides of the street. Potential width being a factor to be considered, the streets in the above examples may be equally wide. The conductance potential of Fig. 4, for example, may be considered in relation to one enormous platoon roughly 300 miles long and easily six lanes wide passing a single point in one hour. The relative power of other systems to conduct traffic may also be compared in this way, keeping in mind that any short signal displays which would restrict the width of the road would also place a restriction on the ultimate conducting power of that road.

14

A completely two-way progressive conventional network would have a comparative conductance of only 120, and a conventional completely one-way progressive network would have a comparative conductance of only 240. Thus, if the Fig. 5 were employed, in a square mile having several of the Fig. 5 units or fractions thereof in the square mile, the total amount of horizontal through traffic to pass a vertical line could be approximately equal to one road-wide platoon of cars 180 miles long and this, added to 180 miles of vertical traffic, equals 360, which is the comparative conductance in relation to other systems, employing the same analysis.

It is, of course, understood that the cams for operating the changes in the signal lights may not necessarily be divided into two equal portions of 180° each, but may be divided into unequal portions of 360° , at at 34 in Fig. 9 by way of example, with all the cams being substantially the same. In this way the system can thereby favor either the horizontal or vertical traffic, as desired, according to the proportionate duration of the two portions of the time cycle. In this connection, it will be understood that, accordingly, this relationship may take into consideration the different loads of traffic.

The effect upon the platoons in Fig. 10 would be to lengthen the potential size of the platoons in one direction and shorten those of the crossing direction. For example, if the end of the horizontal platoon arrows are extended because of the greater duration of the horizontal Go period, then the front of the vertical platoon arrows would automatically be shortened due to the corresponding delay of the vertical Go displays of opposite phase.

Certain characteristics are inherent in the primary system of primary-secondary networks. The basic control sequences on secondary roads relate to opposite direction equivalents, whereas on the primaries, they relate to opposite direction extremes in which one extreme is fast and the other is slow. The controls relating to equivalents are coordinated to those relating to extremes. The faster extreme is predominant.

Extreme control sequences as provided for on primaries possess certain multiband characteristics of special merit, particularly the band of a like speed to that of the opposite predominant speed, which comes into use only by splitting the cycle unequally in relation to the proportionate length of the stop signaling interval along the primary, which is as follows:

Predominant extreme flow	Stop interval facing the primary
$\frac{1}{4}$ cycle	under $\frac{1}{2}$ cycle
$\frac{1}{2}$ cycle	under $\frac{1}{4}$ cycle
$\frac{3}{4}$ cycle	under $\frac{1}{4}$ cycle

Although this commences a continuing series, it is the first three above that are of the greatest value to automotive traffic expedition. These three are within primary-secondary networks, making it possible to utilize a primary road for predominately one-way traffic, while also efficiently processing a return flow of non-predominant traffic at substantially the same speed. Thus special purpose utility would be substituted for maximum conducting power.

As the point at which the extra band comes into use is relative to the point at which crossing secondary progression may be impeded, caution should be exercised not to use this feature except where essential. Employments in which secondaries may not cross are the most receptive to one-way preference, two-way coordinated primaries, as for example on a vertical road as shown in Figs. 1 and 2. This is a special provision for obtaining additional but limited progression in a second direction. However, two-way flows for short distances on primaries are of course possible in signaling interval overlaps,

Also, the use of a second direction non-progressive or random flow upon a primary, would not avoid the invention, if the non-stop operating relations and procedures shown were employed.

Also, it will be noted that in the different road systems of Fig. 1 to 8 the numbers therein, indicating the cam positions, are all consistent with one another, although in some instances some of the numbers are omitted therefrom. However, this does not preclude the special operation of signals in any manner concordant with the continual coordinated platoon progressions which would occur through platoon dispositions, for example as in Fig. 10, especially with respect to signals at locations equivalent to positions designated *a* and *b*.

Inasmuch as the actual conditions of road arrangements in which to apply the progressive networks vary considerably, modifications of my invention may be made according to the various street directions, irregularities, proportions, dimensions and particular traffic problems. It is, accordingly, apparent that the examples and illustrations given hereinabove are not meant to be limitations of the invention but are presented for the purpose of illustration and clarification, in order that others skilled in the art can apply the same in use and so as to modify the same when desirable, as may be best suited to the conditions of the particular road system adopted.

I claim:

1. The process which comprises, establishing a flow of solely-one-way vehicular traffic on two sets of primary roads, one of which sets crosses the other, in each of which sets the traffic on alternating primaries runs in opposite directions, having also a set of secondary roads, of which secondary set each road is at the side of a primary road and of which secondary set at least one road is between primary roads having oppositely moving traffic on successive primary roads, establishing a flow of traffic on said secondary set of roads, and controlling the flow of traffic crossing on said primary and secondary roads by maintaining vehicular groups on each of the roads which advance continuously as non-stop traffic on all the primary and secondary roads.

2. The process which comprises, establishing a flow of solely-one-way vehicular traffic on two sets of primary roads, one of which sets crosses the other, in each of which sets the traffic on alternating primaries runs in opposite directions, having also a set of secondary roads, of which secondary set each road is at the side of a primary road and of which secondary set at least one road is between primary roads having oppositely moving traffic on successive primary roads, establishing a flow of traffic on said secondary set of roads, and controlling the flow of traffic crossing on said primary and secondary roads by maintaining vehicular groups on each of the roads which advance continuously as non-stop traffic on all the primary and secondary roads, in a succession of equal time divisions for the respective vehicular groups, which time divisions continually recur in each set of roads in a $\frac{1}{8}$ division of a time-unit cycle.

3. The process which comprises, establishing a flow of solely-one-way vehicular traffic on two sets of primary roads, one of which sets crosses the other, in each of which sets the traffic on alternating primaries runs in opposite directions, having also a set of secondary roads, of which secondary set each road is at the side of a primary road and of which secondary set at least one road is between primary roads having oppositely moving traffic on successive primary roads, establishing a flow of vehicular traffic compatible with either direction and therefore with both directions on said secondary set of roads, and controlling the flow of traffic crossing on said primary and secondary roads by maintaining vehicular groups on each of the roads which advance continuously as non-stop traffic on all the primary and secondary roads.

4. The process which comprises, establishing a flow of solely-one-way vehicular traffic on two sets of primary roads, one of which sets crosses the other, in each of which sets the traffic on alternating primaries runs in opposite directions, having also a set of secondary roads, of which secondary set each road is at the side of a primary road and of which secondary set at least one road is between primary roads having oppositely moving traffic on successive primary roads, establishing a flow of

5 10 15 20 25 30 35 40 45 50 55 60 65 70 75

vehicular traffic compatible with either direction and therefore with both directions on said secondary set of roads, in a succession of equal time divisions for the respective vehicular groups, which time divisions continually recur in each set of roads in a $\frac{1}{8}$ division of a time-unit cycle.

5. The process which comprises, establishing a flow of solely-one-way vehicular traffic on two sets of primary roads, one of which sets crosses the other, in each of which sets the traffic on alternating primaries runs in opposite directions, having also a set of secondary roads, of which secondary set each road is at the side of a primary road and of which secondary set at least one road is between primary roads having oppositely moving traffic on successive primary roads, establishing a flow of

30 35 40 45 50 55 60 65 70 75

vehicular traffic compatible with either direction and therefore with both directions on said secondary set of roads, and controlling the flow of traffic crossing on said primary and secondary roads by maintaining vehicular groups on each of the roads which advance continuously as non-stop traffic on all the primary and secondary roads, said secondary roads having a secondary road crossing said first mentioned secondary set.

6. The process which comprises, establishing a flow of solely-one-way vehicular traffic on two sets of primary roads, one of which sets crosses the other, in each of which sets the traffic on alternating primaries runs in opposite directions, having also a set of secondary roads, of which secondary set each road is at the side of a primary road and of which secondary set at least one road is between primary roads having oppositely moving traffic on successive primary roads, establishing a flow of

40 45 50 55 60 65 70 75

vehicular traffic compatible with either direction and therefore with both directions on said secondary set of roads, and controlling the flow of traffic crossing on said primary and secondary roads by maintaining vehicular groups on each of the roads which advance continuously as non-stop traffic on all the primary and secondary roads, in a succession of equal time divisions for the respective vehicular groups, which time divisions continually recur in each set of roads in a $\frac{1}{8}$ division of a time-unit cycle, said secondary roads having a secondary road crossing said first mentioned secondary set.

7. The method of routing vehicular traffic repeated at selected apportionments in a time cycle from Go to Stop and vice versa at selected crossing positions of a road network containing two sets of primary one-way roads, one of which sets crosses the other, in each of which sets the traffic on alternate primaries is established in opposite one-way directions, and containing a set of secondary roads some of which are located between the roads of one of said primary sets for controlling traffic so as to permit simultaneous progression in at least four road directions, comprising, at selected crossings along the crossing primaries in their respective one-way directions, the signaling of Go indications substantially $\frac{1}{8}$ cycle later in time from primary to primary crossing positions, in cycle with $\frac{1}{8}$ time cycle later in an opposite direction, also, at selected crossings along the primaries in their prescribed one-way directions from crossing primaries to points of crossing secondaries, the signaling of

Go indications substantially $\frac{1}{8}$ cycle later in time than the first mentioned signaling, in cycle with $\frac{1}{8}$ time cycle later in the opposite direction, also at selected crossings along the primaries in their prescribed one-way directions from crossing secondaries to points of successive crossing primaries, the signaling of Go indications substantially $\frac{1}{8}$ cycle later in time than the just mentioned signaling, in cycle with $\frac{1}{8}$ time cycle later in the opposite direction, also, at selected crossings along the secondaries at positions where they cross primaries, the signaling of Go indications within opposite phases of the time cycle to the Go indications across the said secondaries.

8. The method of routing vehicular traffic repeated selected apportionments in a time cycle from Go to Stop and vice versa at selected crossing positions of a road network containing two sets of primary one-way roads, one of which sets crosses the other, in each of which sets the traffic on alternate primaries is established in opposite one-way directions, and containing a set of secondary roads some of which are located between the roads of one of said primary sets for controlling traffic so as to permit simultaneous progression in at least four road directions, comprising, at selected crossings along the crossing primaries in their respective one-way directions, the signaling of Go indications substantially $\frac{1}{8}$ cycle later in time from primary to primary crossing positions, in cycle with $\frac{1}{8}$ time cycle later in an opposite direction, also, at selected crossings along the primaries in their prescribed one-way directions from crossing primaries to points of crossing secondaries, the signaling of Go indications substantially $\frac{1}{8}$ cycle later in time than the first mentioned signaling, in cycle with $\frac{1}{8}$ time cycle later in the opposite direction, also at selected crossings along the primaries in their prescribed one-way directions from crossing secondaries to points of successive crossing primaries, the signaling of Go indications substantially $\frac{1}{8}$ cycle later in time than the just mentioned signaling, in cycle with $\frac{1}{8}$ time cycle later in the opposite direction, also, at selected crossings along the secondaries at positions where they cross primaries, the signaling of Go indications within opposite phases of the time cycle to the Go indications across the said secondaries, also, at selected crossings along the secondaries at positions where they cross secondaries, between primaries of both said primary sets, the signaling of Go indications within $\frac{1}{8}$ cycle later in the direction of travel from the preceding Go signaling indications at the primary-secondary crossings, and in which the indications thus provided along the secondaries are consonant with two-way progression independent of the traffic movement prescribed along the secondary roads.

9. The process as set forth in claim 7 including adjacent primary pairs of like direction and adjacent secondary pairs of roads, which secondary roads run individually with two-way traffic, or in either direction with one-way traffic.

10. The method as set forth in claim 7 including adjacent primary pairs of like direction and adjacent secondary pairs of roads, which secondary roads run individually with two-way traffic, or in either direction with one-way traffic, and establishing the flow of traffic across the pairs in $\frac{1}{8}$ cycle steps from pair to pair or in $\frac{1}{16}$ steps from road to road.

11. The process as in claim 1, in which traffic control sequences along secondaries relate to opposite direction equivalents as distinguished from extremes, coordinated with controls along each primary sequenced in opposite direction extremes.

12. The process as in claim 1, in which traffic control sequences along secondaries relate to opposite direction equivalents, coordinated with controls along primaries, sequenced in

$$\frac{1}{n}$$

divisions of a cycle, in a direction of predominant flow, complemented in cycling, to

$$\frac{n-1}{n}$$

in the opposite direction, n being more than 3.

13. The process as in claim 12, in which n in one crossing direction is 8, and in the other crossing direction is 4.

14. The process as in claim 12 in which n is 8 and secondaries cross in the network.

15. The process as in claim 12 in which n is more than 3 and less than 9 or multiples thereof and secondaries cross in the network.

16. The process as in claim 12, wherein in addition to the said solely one-way vehicular traffic which remains predominant, obtaining multiband progression and substantially-like two-way traffic speed in opposite directions of one crossing direction, on a given primary road, by a signaling cycle split to crossing Go intervals of under

$$\frac{2}{n}$$

across the given primary, crossed by more than

$$\frac{n-2}{n}$$

along the given primary, n being an even number greater than 3.

17. The process as in claim 5, in which traffic control sequences along secondaries relate to opposite direction equivalents, coordinated with controls along primaries in which frequency speed a , and frequency speed b , expressed in lowest term number relation, make the number of major crossing areas per repetitive span c , a herein being 1, b herein exceeding 3, and a and b herein being opposite direction sequential flows adding to c .

18. The process as in claim 5 in which primary traffic bands are established to the side of secondary bands, greater in length by $\frac{1}{8}$ to $\frac{1}{8}$ of a time unit cycle, than the secondary bands.

UNITED STATES PATENT OFFICE
CERTIFICATE OF CORRECTION

February 23, 1960

Patent No. 2,926,332

John K. Masten

It is hereby certified that error appears in the printed specification of the above numbered patent requiring correction and that the said Letters Patent should read as corrected below.

Column 3, line 39, for "A.-C. current" read -- alternating current --; column 9, line 44, after "time-points" for 1, 8, 5, 6, 4, 1, 2, read -- 1, 8, 5, 6, 5, 4, 1, 2, --; column 10, line 2, a new paragraph should be made beginning with "Further, there may be a"; column 12, line 6, after "stopping" insert a comma; line 72, before "secondary" insert -- non-dotted --; column 13, line 67, after "Fig. 4" insert -- over a square mile area --; column 14, line 16, for "at", first occurrence, read -- as --; lines 57 and 58, strike out "are of the greatest value to automotive traffic expedition. These three are" and insert instead -- may be --; column 16, line 12, for "in a succession of equal time divisions for the re-" read -- and controlling the flow of traffic crossing on said --; line 16, for "in succession" read -- in a succession --; column 17, line 54, for the claim reference number "7" read -- 5 --.

Signed and sealed this 25th day of October 1960.
